UNITED STATES PATENT OFFICE

143,375

DESIGN FOR A COMBINED FRUIT DISPLAY AND CONTAINER UNIT

George W. Wallace, Waynesboro, and James W. Trew, Gettysburg, Pa.

Application May 15, 1945, Serial No. 119,551

Term of patent 14 years

(Cl. D80—5)

To all whom it may concern:

Be it known that we, George W. Wallace and James W. Trew, citizens of the United States, respectively, residing at Waynesboro, in the county of Franklin, and Gettysburg, in the county of Adams, and State of Pennsylvania, have invented a new, original, and ornamental Design for a Combined Fruit Display and Container Unit, of which the following is a specification, reference being had to the accompanying drawing, forming part thereof.

Figure 1 is a view in perspective of a Combined

Fruit Display and Container Unit embodying our new design;

Figure 2 is a view in end elevation;

Figure 3 is a view in top plan; and

Figure 4 is a view in bottom plan.

We claim:

The ornamental design for a combined fruit display and container unit, substantially as shown.

GEORGE W. WALLACE.
JAMES W. TREW.
